Société Anonyme, Rijmenam-Malines, Belgium, a cor-
poration of Belgium

Filed July 18, 1966, Ser. No. 3,104

Term of patent 14 years

(Cl. D13—1)

The sole figure of the drawing shows an extruded cellular panel for furniture representing my design.

The center is broken away and one end thereof is shown fragmentarily to indicate an article of indefinite length and width.

I claim:

The ornamental design for an extruded cellular panel for furniture, as shown and described.
